(57) **CLAIM**

The ornamental design for a three dimensional ornament, as shown and described.

DESCRIPTION

FIG. 1 is a perspective view of the three dimensional ornament showing a first embodiment of our new design containing a hummingbird and flower central design element;

FIG. 2 is a top plan view of FIG. 1;

FIG. 3 is a side elevational view of FIG. 1;

FIG. 4 is an enlarged scale side elevational view of a second embodiment wherein the central design element is altered to replicate a cardinal;

FIG. 5 is a perspective view showing a third embodiment wherein the central design element contains a circularly enclosed hummingbird and flower;

FIG. 6 is a top plan view of FIG. 5;

FIG. 7 is a side elevational view of FIG. 5; and,

FIG. 8 is an enlarged scale side elevational view of a fourth embodiment wherein the central design is altered to replicate a circularly enclosed cardinal.
